UNITED STATES PATENT OFFICE

2,640,458

MACHINE FOR PRINTING AND POWDERING SHEETS

Arthur C. Sias, Weston, Conn., assignor to Commercial Decal, Inc., Mount Vernon, N. Y., a corporation of New York

Application March 17, 1950, Serial No. 150,321

29 Claims. (Cl. 118—46)

1

This invention relates to new and useful improvements in machines for powdering sheets and has especial reference to devices for printing decalomania sheets and then powdering them with suitable pigments. It is to be understood that when the word "powdering" is used it is meant to include not only the application of color to the sheet, but also the application of flour or similar material to the sheets for dusting the same when desired.

Background

In conventional printing processes, the pigment is incorporated in the printing ink.

In ceramic decal printing, only a few colors are printed with the pigment incorporated in the printing ink. Most of the colors are applied subsequent to the printing operation in the following manner:

The printing of the image on the sheet of decal paper is done with varnish in which no pigment is incorporated. The pigment is subsequently applied to the image by dusting the entire sheet of paper with the dry color. The color thus dusted adheres to the printed varnish image. Excess color is removed from the sheet, leaving the desired image with the color attached to the previously printed varnish.

For many years this particular method has been achieved by first printing the varnish on flatbed printing presses, using lithographic stones as printing plates. After the varnish was thus printed, the sheets were hand-fed through a machine which applied the pigment. This machine is known in the trade as the powdering machine.

The hand-fed powder machine consisted of a feed board; front stop guides to which the sheet is fed or positioned; a cylinder approximately 20" in diameter which is equipped with a gripper mechanism to take the sheet; an elevating mechanism which raises the fed sheet to the cylinder grippers; a color fountain which holds the color against the cylinder and through which the sheet passes as the cylinder and the sheet rotate; oscillating buffer pads which distribute the color over the sheet and cause intimate contact of the color with the previously printed varnish; feed rollers which bear on the sheet pressing sheet against the cylinder; shooft pins which push the front edge of the sheet away from the cylinder when the grippers open; stripper fingers which intercept the front edge of the sheet of paper as the cylinder rotates and guide the sheet off the cylinder and into a collecting box.

The method above described has hitherto been

used and produces the work with definite limitations as to method and apparatus which make it impossible to produce greater quantities of work and also make it impossible to produce certain types of work.

As indicated above, the varnish has been printed on a flat-bed lithographic press using litho-stone plates. It is not considered practical to make stone plates by photographic means. It is desirable to make plates by photographic means. Plates made by photographic means are usually metal plates instead of stone. Attempts have been made to print our type of work using metal plates by photographic means by using such plates on the aforementioned flat-bed presses. Results have not been satisfactory or practicable.

Further limitations of the flat-bed litho press is that of speed. This type of press is reciprocating and is limited to approximately 1,000 sheets or impressions per hour. By substituting the modern offset rotary lithographic press for the flat-bed press, the above limitations are avoided. Metal plates made photographically can be successfully and practically printed on modern cylinder presses in producing our type of work. Such a press may be operated in excess of 5,000 sheets or impressions per hour.

This brings us naturally to the limitations of the hitherto known powdering machine. Being hand-fed at 1,000 sheets an hour it obviously could not keep pace with a cylinder press operating at 5,000 sheets an hour. It was then attempted to use a machine similar to the hand-fed powder machine but placed at the end of the offset printing machine in such a manner that the sheets dropping off the delivery of the offset press would fall on to the feed mechanism of the powder machine, both machines being driven in synchronism. A pile delivery was added to the powder machine to replace the collector box of the hand-fed model. This arrangement was used and caused so much trouble that as a natural and inevitable consequence our present new machine was developed and forms the basis of the herein invention.

The first difficulty with the old machine had to do with the delivery of the printed sheet to the powdering unit. In the old machine the sheet was under positive control until it was dropped on to the traveling feed tapes of the old powder machine feeder. At this point the positive feed of the sheet was lost and it was just floating on moving tapes. The function of these tapes was to bring the sheet down to the front

stop guides of the powder machine in such position and at the proper time so that the elevating mechanism could introduce the sheet into the powder machine cylinder gripper. In order to effect this result it was necessary that the sheet be properly positioned at the front stop guides of the feeder at the proper instant. To accomplish this with a fast moving sheet of paper that was under no positive control, but just floating on moving tapes was found impracticable. It should be remembered at this point in the old process that the sheet has been printed with varnish and was not yet dusted with color. Any attempt to use rollers or other mechanism on the top of the sheet to obtain some measure of control would be most likely to smear or disturb the freshly printed varnish image. There are other objections relating to the mechanical means for feeding the sheet to the powder cylinder grippers but the essential point is that up to this time the sheet has not been under positive control after it left the delivery of the offset press until it reached the grippers of the powder cylinder.

The effect of this previous difficulty in controlling the sheets passing from the printing press to the cylinder of the powder cylinder has been that the sheet is out of control and consequently there are frequent "misses." The sheets are thus piled up in the machine causing not only loss of the sheets which miss and get fouled up, but also spoiling succeeding sheets until the machine is brought to a stop. These pile-ups also endanger the equipment itself, sometimes causing smash-ups. Furthermore, one of the most serious effects outside of lost production and spoiled sheets is the effect of frequent stops on the job as a whole. Uniformity of the printing on a complete job, say 5,000 to 10,000 sheets, is best achieved by continuous operation of the printing press. Frequent stops and starts results in tremendous variation in the printing of the entire job and makes the job unacceptable to the customer.

It is therefore a main object of this invention to eliminate this loss of control of the sheets as they pass from the printing press to the powder cylinder.

Another and similar difficulty with respect to the feed of the sheet around the powdering cylinder in the old machine has been that the sheet is held on the cylinder by one long gripper which acts also as the gap closer. As the cylinder and sheet rotate, the sheet is first passed through the color fountain, then under the oscillating rubbing pads, after which it has been necessary to deliver the sheets from the cylinder to the chain grippers of the pile delivery. Due to the fact that the sheet is held to the cylinder by one long continuous gripper, it is impossible to grab the sheet with the chain grippers without first opening the grippers on the cylinder. Of course, just as soon as the gripper thus opens, the control of the sheet at this point is lost. Previously, means had been provided on the old machine to attempt to maintain control of the sheet by placing so-called feed rollers or collars in such a manner that they bear on the sheet, pressing it against the cylinder and rotating in synchronism with the cylinder surface. This was done to keep the sheet moving with the cylinder. However, it must be noted that in the old machine part of the sheet still remains under the oscillating pads when the gripper opens, thus putting the full responsibility of moving the sheet against the drag of the pads upon the feed.

rollers. Pressure is required to do this but on the other hand excessive pressure of these rollers cause marks on the sheet and slurring of the freshly printed image on the surface of the sheet with which the rollers contact. In addition, even excessive pressure does not guarantee that the sheet will not slip back occasionally. After the cylinder gripper opens, it is necessary for the grippers of the chain delivery bars to intercept the front edge of the sheet, this edge no longer being positively held. It is necessary for the front edge to be in position at or outside of the surface of the cylinder in order for the grippers to intercept it. To accomplish this, so-called shoo-fly pins have been used. These are pins in the cylinder positioned under the cylinder grippers. When the grippers open, these pins push out from the surface of the cylinder against the underside of the leading edge of the sheet, pushing it away from the surface of the cylinder so that the chain bar grippers of the delivery unit can take hold of the sheet. This arrangement has been found far from positive and depends too much upon the straightness or curl of the paper. If the leading edge of the sheet is curled away from the cylinder, the chain bar grippers miss it on one side. If the curl is toward the cylinder, they miss it on the other side. The same conditions exist if the sheet is too limp or too stiff. Furthermore, if the drag on the sheet caused by the rubbing pads is greater than the forward pull caused by the feed rollers, the sheet tends to slip back when the cylinder gripper is opened and the shoo-fly pins miss the front edge of the sheet.

A second object of this invention is to provide means to insure that the drag on the sheet when the grippers open is eliminated and that the transfer of the sheet from the powder cylinder to the pile-up delivery mechanism is positive and that the sheet, during this transfer, is under full and positive control.

Still another difficulty with the former machine has to do with the inadequate and uneven deposit of color on the sheet. As previously stated, the process of printing described involves printing the design in unpigmented varnish on the sheet first, and then subsequently dusting the dry color on. In the previous form of machine there was employed one color fountain and three oscillating pads disposed thereafter along the surface of the powdering cylinder. It has been found, however, that with the use of the cylinder printing press instead of the old flat-bed press the speed of operation and delivery of the sheets is much faster and therefore the old cylinder was not sufficient to handle the delivery unless its speed was jumped up by excessive amounts. Furthermore, with the use of two fountains on the old machine, the second fountain would be too close to the vertical center of the cylinder surface.

It is therefore another object of this invention to overcome this deficiency whereby the improved cylinder can handle the faster delivery from the printing press and also accommodate the larger number of fountains and pads necessary to thoroughly apply the powder and not smear the surface of the sheets.

A further difficulty with the old machine and its use with more fountains and pads has to do with the possibility of causing inadequate deposit of color and an uneven deposit of color. When additional color fountains are added to the old cylinder more oscillating dusting or rubbing

pads must be added. With the old cylinder this would require that some of the added pads being disposed on the quadrant of the cylinder extending from the vertical center of the cylinder on the downward path of the cylinder. Here again we have the aggravated condition where the collar would be riding on the cylinder in a downward path which would cause streaking and marking of the fresh image due to the jamming affect of the color as it is carried by the cylinder against the oscillating pads. The adjustment of the pads with respect to the cylinder and the pressure of the pads on the cylinder presented a problem. Another problem has been to provide simple means whereby this pressure can be easily and quickly varied to suit the needs and that the pads can be independently lifted away from the cylinder if at any time a particular pad picks up some bit of color or substance that will mark the sheet.

It is thus a still further object of the invention to provide means to overcome these defects.

Still another difficulty encountered with the old machine is due to considerable spoilage of work due to the fact that excess color is carried along with the sheet. This color accumulates in the pile, packs unevenly on the design and either results in spots of heavy color in the finished work or is the cause of rub marks resulting when too vigorous cleaning methods are employed. In addition to the loss due to spoiled printed sheets, there is also a tremendous loss or waste of the color itself. Many of the colors employed cost \$35.00 or more a pound. Another disadvantage of this excess of color on the sheet is the limitation it imposes on subsequent operations. The sheets cannot be fed through the cleaning machines, practically, in an automatic feeder because such feeders depend upon air blowers to separate the sheets in feeding. Air blown in between the sheets covered with excess color creates a cloud of color powder which is very difficult to collect and exhaust. Thus production is limited to hand-fed machines at a rate of approximately 1,000 sheets per hour instead of 5,000 or more sheets per hour in an automatic feed machine.

The reason for dirty sheets on the old machine is outlined briefly as follows:

A. Only has one color fountain. Pressman tosses additional color between pads.

B. Only three oscillating pads.

C. Incorrect positioning of the oscillating pads on the cylinder too near top center.

D. The cylinder gripping bar is also the gap closer. There is always a deposit of a line of color along the edge of the gap closer on the sheet of paper. This is not readily removed before the gap closer is opened. However, on the old machine the gap closer being also the gripper, when the gap closer is opened, the sheet is no longer held by the gripper. This makes it difficult to provide means for removing the color.

E. Accumulation of color at the back edge of the gripper bar.

F. Feed rollers.

G. No means to clean back of the sheet.

It is therefore still another object of the invention to provide means to overcome the above mentioned defects.

A further problem in connection with prior 70 powdering machines is related to the extreme difficulty of adjusting and relatively timing the various devices so that perfect synchronization results and the machine may be used day in and day out without stoppage for readjustments. 75

Another problem had to do with the fact that the operation of the grippers on the drum when receiving a sheet from the press has not been hitherto independent from the operation of the same grippers when they are called upon to turn over this sheet to the grippers on the chain delivery mechanism of the pile-up device. It is therefore an object of this invention to provide independent means for adjusting the various grippers on the machine, especially on the drum and to permit independence of adjustment of the operation of said grippers on the drum when they deliver the sheets to the pile-up device.

Further and more specific objects, features, and advantages will more clearly appear from a consideration of the detailed specification herein-after set forth especially when taken in connection with the accompanying drawings which illustrate a present preferred form which the invention may assume and which form part of the specification.

In brief and general terms the improved machine which is designed to overcome the difficulties and defects of the old machine as above set forth, includes the combination of a rotary high speed off-set printing press in which the designs in varnish are printed on the sheet, a large powder cylinder of such diameter that its circumference will accommodate several sheets at a time, and a pile-up delivery unit associated at the opposite side of the powdering cylinder to receive the printed and dusted sheets.

A vital feature of this set-up is that means are provided in the form of grippers which seize the printed sheet as soon as it passes the printing rollers or cylinders and holds its front edge, thus gripped, under positive control as it is passed to a similar set of grippers on the powder cylinder. This arrangement is such that one set of grippers do not let go of the sheet edge until the other set has established gripping engagement. In passing from the powder cylinder to the pile-up delivery mechanism the same action takes place, namely, the grippers on the powder cylinder do not let go of the sheet edge until grippers on the delivery chains have seized this edge to pass it to the pile-up device. In this general manner it is seen that the sheet is thus under direct and positive control at all times and never for an instant floats free in its passage from the printing unit to the pile-up unit. Thereby the defects and difficulties previously enumerated and described are definitely avoided.

As indicated above, the old powder machine was a separate machine placed at the end of the off-set press. The sheets dropped off the chain delivery of the press onto the feeder of the powder machine. In the new machine the design is such as to make the off-set press and powder machine one complete unit. The powder machine is an integral part of the unit. The pile delivery of the off-set press as assembled by the manufacturer is removed; the new powder machine is assembled integral with the off-set press and the pile delivery of the press is then assembled at the delivery end of the powder machine. Gripper bars mounted on chains take the sheet from the impression cylinder of the off-set press in the same manner that the chain delivery did before it was removed from the press. These gripper bars carrying the sheet take it to the grippers on the powder cylinder of the new powder unit. They do not let go of the sheet until the grippers on the cylinder of the powder machine take hold of it. Continuous operation

7 without dropping or missing sheets is thus achieved, thus eliminating the defects and troubles above enumerated.

A further feature of the invention has to do with eliminating drag on the sheets when the cylinder grippers open. In order to achieve this the new powder machine cylinder is of such a size that all work on each sheet is accomplished before the cylinder grippers open, i. e. the distance from the point at which the grippers open to the last unit which provides a drag on the sheet is equal or greater than the dimension of the sheet of paper along the surface of the cylinder in the direction of its travel. The size of powder cylinder which meets this requirement is one which is 4 times the diameter of the printing cylinder in the off-set press. Furthermore, the mechanism for transferring the sheet from the powder machine cylinder to the chain delivery bar grippers on the new machine is identical with that which is used in transferring the sheet from the other chain bar grippers which brought the sheet to the cylinder grippers. Thus positive control of the sheet is maintained throughout its entire trip through the offset press, through the powder machine, and to final deposit in the pile delivery. The particular details of the gripper devices and their operation are set forth in detail in the subsequent specification.

With reference to the prevention of dirty sheets on the new machine, it may be briefly stated that defect items A, B, and C are eliminated by providing more fountains and pads and making this possible by using a much larger powdering cylinder in the manner above set forth.

Item D above, relating to the defect of depositing a line of color along the edge of the gap closer, is solved generally by reason of the fact that the grippers which hold the sheet on the new machine are separate from the gap closer mechanism. This means that the gap closer can be opened while the grippers are still holding the sheet and the line of color on the front of the sheet in a position corresponding to the edge of the gap closer is removed while the sheet is firmly held by the grippers. This briefly is achieved by providing a mechanism which produces a gentle wiping along this portion of the sheet.

With regard to defect noted under item E above, it is generally solved by eliminating the possibility of collection of color at the back edge of the gap closer by way of adjusting the fit of the gap closer at this point to prevent such collection.

With regard to defect item F above mentioned, this is solved by eliminating the need for feed rollers in that the sheet is held by the grippers until after its rear edge leaves the pads and is not released until the grippers of the pile-up delivery chains take over as before stated. Thus no feed rollers are required and this difficulty is eliminated.

With regard to defect item G above mentioned, the old machine had no means for cleaning the back of the sheets on which color might have collected. In the new machine, this problem is solved in general by utilizing a suction action on the sheet after the pile-up delivery grippers have seized it in order to more effectively hold it in more intimate contact with wiper rollers disposed in contact therewith so as to effectively remove the last trace of color from the back of the sheet.

It is, of course, to be understood that further

features and advantages of the new machine are set forth and described in detail in the following detailed specification and to be understood in connection with the drawings which form part of the specification.

A preferred present form which the invention may assume is illustrated in the drawings, of which—

Fig. 38 is a section of the same construction taken on the line 38-38 of Fig. 37.

Referring now to the specific details and structure of the preferred form of the machine shown in the drawings, it will be noted in respect to Fig. 1 that I have schematically represented the entire machine which generally comprises a pile A of sheets to be passed to the rotary off-set printing press B wherein the design is printed thereon in varnish after which a chain delivery mechanism C carries the printed sheets to a powder cylinder device D, where the design is dusted with colored powder. After thus being treated a second chain delivery mechanism E passes the printed and dusted sheets to a pile-up device F.

Drive of press and powder cylinder

In general, the units A, B, and C above mentioned are well known mechanisms for delivering sheets to a rotary press and then gripping them and passing them to a powder cylinder. Insofar as the construction has been modified to involve invention, it will be particularly set forth as such. With reference to Figs. 1 and 2, the sheet from the pile A is delivered in any suitable and well known manner to the press B and in such passage it passes between cylinders 40 and 41 to receive an impression thereon of the desired design in varnish or similar substance. Fig. 2 is a general view looking from the rear of Fig. 1. The sheet then passes around a transfer mechanism 42. As it leaves the impression cylinders it is gripped in a well known manner and is transferred by suitable chain delivery mechanism 43 to a transfer point where the control of the sheet is taken over by grippers on the powder cylinder D in a manner subsequently to be described.

It is to be noted that the drive of these units is from a motor 45 by belt 46 to a pulley 47. The shaft of pulley 47 has a sprocket 48 thereon connected by chain 49 to a sprocket 50 on transfer shaft 51 which also carries a gear 52 meshing

with a gear 53 connected to the shaft 54 of the powder cylinder D.

The shaft of pulley 47 also has thereon a sprocket 55 over which runs a connection 56 to a sprocket 57 on a shaft 58 carrying a gear 59 meshing with a gear 60 on shaft 61 having a gear 62 meshing with a gear 63 on shaft 64. The gear 63 is mechanically associated in a manner not shown, but well known, with the blanket cylinder 40 and impression cylinder 41 previously mentioned and with the plate cylinder 65 which bears on the cylinder 40. In Fig. 2 is shown an adjustable tensioning plate 66' bearing against the lower run of the chain 49 to keep it in any well known manner under desired tension.

The sheets of material printed in the press which is generally of the type known as the Harris press are gripped as soon as they are printed between the rollers 40 and 41 by grippers mounted on chains such as 66 shown in Fig. 3. At the forward end of the chain delivery mechanism C adjacent the powder cylinder D is disposed the shaft 51 shown in Fig. 1 and this shaft has thereon sheet wheels 67 supporting the sheet adjacent the surface of the cylinder D, and also sprockets 68 over which the chains 66 shown in Fig. 3 pass. (See Fig. 7.)

The path of the chains and the sheets is somewhat schematically shown in Fig. 2(a) in which we have located the shaft of transfer mechanism 42, and the center of shaft 51. The general flow of the chains 66 and the sheets is indicated by the line 69 and it is observed that the chains with the sheets pass around the roller 42 in the direction of the arrow, then along a supporting plate or guide pad 70, around a guide wheel 71, and then around the sprockets 68 of Fig. 7. These chains carry gripper devices to be later described and as these grippers pass in adjacency to the surface of the powder cylinder, grippers on the powder cylinder take hold of the sheet and those on the chain delivery are released. After the delivery chains pass around the sprockets 68 they pass over tension wheels 72 which are adjustably mounted. After this they are passed between guide plates 73 and 74 and led back to the sprockets on the transfer mechanism 42.

Grippers on chain delivery

Returning to Fig. 7 there are shown two cams 75 and 76. These cams are well known in the Harris chain delivery mechanism but it may be briefly stated that cam 76 as shown in Fig. 9 is adapted to and does open the gripper fingers as the sheet is to be transferred to the grippers on the cylinder D and the cam 75 acts to support the gripper supporting bar 80 as it swings around while the grippers thereon are being operated.

The cam 76 is loose on shaft 51 and is connected to auxiliary anchor shaft 75' by means of an adjustable link 76' so that the timing of this cam may be precisely established.

Referring now to Figs. 3 to 10 inclusive, it is clear that the sheets are moved from the press to the powder cylinder and are advanced by being gripped by gripper fingers 77 mounted on an oscillatable shaft 78 which is supported on suitable brackets 79 from another shaft 80 extending between the chains 66 and fixed thereto. With each finger 77 there is related an anvil surface 81 formed on a collar 82 fixed to shaft 80. One of the brackets 79, the center one shown in Fig. 3, has thereon a roller 83 which is adapted to ride in a curved slot 84 on the cam 75 shown in Fig. 7.

11

This roller 83 riding in the slot 84 will hold the shaft 80 at its center from being deflected laterally under the strain of the gripper operating mechanism. Referring to Fig. 7 it is to be noted that the supports for the cams 75 and 76 are embracing the shaft 51, which rotates, but are not fixed thereto so that although the shaft may rotate the angular position of the cams remains fixed at any given time for important reasons which will become subsequently apparent.

With reference to Figs. 3, 5 and 6 it will be seen that the means for oscillating the fingers 77 comprises a bracket 85 fixed to shaft 80 and this carries a pivoted lever 86 with a roller 87. The lever 86 is fixed to oscillatable shaft 78 and when it is moved on its pivot the shaft 78 is turned to tilt the gripper fingers thereon. The lever 86 has at one end a stop arm 88 to limit against the bracket 85 to prevent too great movement of the lever in one direction. Spring 89 under compression tends to move the stop against its limiting position when the cam roller 87 is not riding on its cam. The cam engaged by roller 87 is the cam 76 shown in Figs. 7 and 9. The angular position of this cam with respect to the horizontal is predetermined so that the grippers will be opened at just the right instant and just after the grippers on the powder cylinder have taken hold, as will be explained.

Powder cylinder and gripper operation thereon

Referring to Figs. 11 to 14 inclusive, it will be seen that the cylinder D is supported on a horizontal axis between two upright frame members 90 and it is driven, as above noted, through the meshing of gear 53 with gear 52 (Fig. 2). The cylinder is provided with four gripper wells 91 (Fig. 14) and in each well is disposed a gripper shaft 92 (Fig. 15) which is rockable about its axis and has rollers 93 and 94 at its opposite ends which extend beyond the cylinder side walls. Referring to Figs. 15 and 16, it will be seen that the gripper shaft 92 has fixed thereon gripper fingers 95. These fingers are movable against respective anvils 96 mounted on anvil blocks 97 embracing loosely the shaft 92. These blocks have set screws 98 and 99 adapted to be moved into abutment with shoulders of the well as indicated in dotted lines in Fig. 16 to limit the swinging motion of the anvils in either direction. A spring 100 around the stop screw tends to move the anvils counter-clockwise to extend slightly beyond the surface of the cylinder D but to permit their movement within said surface when pressed against by the gripper fingers 95.

Means for operating gripper shaft

Referring to Figs. 11, 12 and 17 it will be seen that each shaft has at each end adjustable blocks 101 carrying the rollers 93 and 94 and to one of these blocks is connected a rod 102 slideable at the other end in a block 103 fixed to the cylinder D. A spring 104 is disposed around the rod 102 between and abutting both the block 103 and the end of rod 104 which is connected to block 101. The normal action of this spring tends to move the block 101 counter-clockwise when not under the influence of cam roller 93 and thus tends to hold the gripper fingers 95 in open position extending outward of the surface of the cylinder D. Referring to Fig. 12 it will be seen that there is a curved elongate cam bar 105. The end of this bar which the rollers 93 first contact is provided with three steps of elevation, 106, 107 and 108, 75

12

and the latter level runs all the way round to the end of said bar as clearly seen in this figure. This bar 105 is mounted on the inner side of the left-hand frame member 90 as seen in Fig. 11. It is to be observed that the rear end of this bar 105 terminates some distance from the stepped forward end just described and in this space and at approximately the lowest point in the travel of the cylinder gripper wells there is disposed a short separate cam bar 109 having front and rear slopes 110 and 111 and a high central level 113. This cam bar meets the rollers 93 and lifts them to close the grippers at this point for a purpose later to be explained. On the cam bar 105 the step 106 starts the closure of the gripper fingers 95, the step 107 effects their engagement with their respective anvils, and step 108 forces the fingers back to depress the anvils and dispose the fingers below the surface of the cylinder D, so as to permit a gap closer, to be later described, to lie flat and flush smoothly with the surface of the cylinder.

Referring now to the operation of the roller 94 at the opposite end of the gripper shaft 92 and shown in Fig. 15, reference may be had additionally to Fig. 21, where there is illustrated a cam 114 fastened to the right hand frame member 90 of Fig. 11. If the relations of the cam bar 105 and cam bar 114 are properly visualized, it will be seen that the roller 93 and consequently the gripper fingers 95 are kept closed until the roller 93 passes the rear end 115 of the cam bar 105. At this point it would drop suddenly and open the grippers immediately were it not for the cam 114 on the other side of the cylinder D which is so positioned that the instant the roller 93 leaves the cam bar 105 the roller 94 rides along the high level 116 of the cam 114 which is at the same level as the high level 108 of the cam bar 105. The roller 94 then passes to the intermediate level 117 of the cam 114 and then to the low level 118. At the high level 116 the fingers 95 are closed and pressed back as before. At the intermediate level 117 they are still closed but move forward, and at the low level 118 they are opened. This permits the grippers on the cylinder D to be opened in a predetermined timed manner so as to permit other grippers on the chain delivery mechanism E to take control before the grippers on the cylinder have let go of the sheets. This transfer mechanism is not shown in detail since it is in essence the same as that shown with respect to the chain delivery C of the sheets from the press B to the grippers on the cylinder D previously described. An adjusting mechanism for this cam 114 is generally indicated by the set screw 119.

In reviewing this grippers operation, it will be noted that the cam 76 (Fig. 9) opens the grippers 11 on the chain delivery mechanism C rapidly at the instant the gripper fingers 95 in the wells 91 have gripped the sheet and not before. The gripper fingers 95 hold the sheets until they are operated by the action between the roller 94 and the cam 114 to let go of the sheet. However, before they let go of the sheet the grippers on the chain delivery mechanism E, which function similarly to the grippers on the chain delivery C, have gripped the sheet to pass it to the pile-up mechanism F. Thus we have a complete control of the sheet from the time it is gripped as it leaves the press until it is released to the pile-up mechanism and there is not the slightest possibility of the occurrence of the troubles previously had

with former machines not provided with this simple and efficient arrangement and which defects have been clearly set forth in the opening of this description.

Gap closers and operating mechanism

Referring now to Figs. 11, 14, 18, 19, 20 and 21, it will be seen that the wells 91 have part of their face open to the periphery of the cylinder D as indicated by the numeral 120 in Fig. 14. When the sheets have been gripped and their ends have been drawn slightly within the cylinder below the surface thereof, it is necessary to close this gap and for this purpose plates or gap closers 121 are provided. These are mounted on arms 122 fixed to a closer cross shaft 123. This shaft extends at each end beyond the side walls of the cylinder D and at the right end shown in Fig. 18 supports a roller 124 by means of arm 125 fixed to the shaft. This roller 124 rides in engagement with a cam bar 126 (Fig. 21) which is mounted fixedly on the inner face of the right hand frame member 90 as seen in Fig. 11. These closers are kept opened by cam action and are closed by spring action. As seen in Fig. 21 when the cam bar 126 is encountered by roller 124 its sloped end will lift the roller 124 and this will cause a rod 127, connected to the arm 128 on the opposite side of the shaft 123, to move back against the action of a spring 129 disposed around said rod and bearing between the arm 128 and a block 130 on the side of the cylinder D through which block the rod slides. The rear downwardly sloping end 126' of the cam 126 is reached and the roller 124 drops after the grippers on the cylinder have gripped the sheet thus allowing the springs 129 to effect the closing of the well gap. In Fig. 19 the closer is shown closed in full lines and open in dotted lines. The forward portion of the closer plate 121 is provided with a long gradual taper so that its front edge 131 is very thin and its outer face will lie flush with the surface of the cylinder D. This flush relation is further effected by the fact that the edge of the well at this side of the gap is sloped inwardly as at 132. The closer as shown has a width less than that of the gap so that the rear end in being positioned is not constricted and will permit an adjustment of the front portion thereof. Therefore when it is in closed position as seen in Fig. 20, there remains a small gap between its rear edge and the other wall of the gap. This is closed by a somewhat resilient plate 133 mounted in any suitable manner on a bracket 134 which is fastened by a bolt 135 to the cylinder D. The forward end of this resilient plate 133 is supported against too much inward movement by means of a rigid bar the curved end of which 136 lies closely adjacent the rear face of the forward end of the plate 133. This bar 136 is bolted at 137 to the bracket 134. The rear upper edge of the closer 121 is tapered inwardly as at 138 so that as it is swung to closed position this edge will be pressed against the forward end of the spring plate 133 and form a snug joint and which is yet somewhat flexible.

Color fountain construction

Referring now to Figs. 22, 23 and 24 the construction and operation of the color fountains are disclosed in a general manner since variations thereof are possible within the scope of the invention. Therein are shown brackets 139 and 140 bolted at 141 to the respective frame members 90 supporting the cylinder D. Slidably sup-

ported on the brackets is a bottom wall 142 of the fountain having lateral flanges 143 resting on inwardly projecting flanges 144 on the brackets 139 and 140. The flanges 143 are provided with slots 145 in which ride bolts 146 fastened to the flanges 144. This permits the guidance of the bottom plate 142 backward and forward. The forward edge of the bottom plate 142 of the fountain is provided with any suitable soft padding such as 147 to prevent leakage of the color powder from the fountain along this edge.

In order to adjust the bottom plate and the whole fountain with respect to the surface of the adjacent cylinder D, there is provided an adjustable screw shaft 148 operated by turning a hand knob 149. This shaft is suitably mounted on the bracket 139 shown in Fig. 22. Laterally extending from the shaft 148 is an arm 150 the outer end of which rides in a notch 151 in the left-hand flange 143 of the bottom wall 142 of the fountain. By turning the knob 149 the bottom plate may be moved forward and backward as desired to adjust the pressure against the cylinder D of the pad 147. The fountain is provided with side walls 152 and 153 which are adjustably supported (see Figs. 22 and 23) from brackets 139 and 140 respectively by any suitable means such as the spacer means and associated parts indicated in these figures by the numerals 152' and 153'. At their forward edges, which are naturally shaped to the curvature of the cylinder D the side walls are provided with padding 154 of any suitable material to prevent leakage of the color from the fountain at these points. The side walls are provided with curved arcuate slots 155, indicated by dotted lines in Fig. 22, into which are slidable a rear wall 156 shown in Fig. 24. Thus this rear wall may be easily slid into and out of operative position as desired for purposes of cleaning, replacement and repair. Thus the fountain may be easily and efficiently adjusted with respect to the surface of the cylinder D so that proper pressure thereagainst is maintained to prevent leakage.

In order to keep the powdered color material within the fountains in condition to lie freely against the wall of the cylinder to coat the design thereon which is impressed in varnish or similar material, it is found necessary to stir the powdered material constantly to keep it from clotting in lumps. This mechanism takes the general form of a series of fingers 157 extending down within the fountain chamber to a point near and along the bottom thereof. These fingers are supported in any desired manner from a bar 158 to the opposite ends of which are fastened arms 159 and 160. These arms extend into respective engagement with bearing brackets 161 and 162 supported from the brackets 139 and 140 and are provided with suitable ball bearing elements 163 to permit the free sliding movement of the arms 159 and 160 back and forth.

As shown at the right in Fig. 23, the arm 160 is connected to one end of a link 164 the other end of which is eccentrically connected to a bevel gear 165 on a shaft 166 supported in a suitable bearing member 167. This gear 165 meshes with a bevel gear 168 on a shaft 169 carrying a gear 170 which meshes with the main gear 53 on the side of the cylinder D. Therefore, as the cylinder D is rotated in the manner hitherto set forth the fingers 157 are reciprocated to keep the material in the fountain stirred up in the desired manner.

15

It is to be noted from the general Figure 1 of this application that there are provided two fountains, the first of which is disposed just above the right hand horizontal plane of the cylinder D and the next one above that with two buffer pad mechanisms between the two fountains and with several additional buffer pad mechanisms above the upper fountain and extending up to the vertical plane of the cylinder.

Buffer pad operating mechanism

Referring now particularly to Figs. 25, 26, 27 and 28 the buffer pad operating mechanisms are shown. These pads are formed of any suitable soft material 171 wrapped around and supported on the bottom plate 172 of T-rail members having a vertical web 173. They may be attached to the plate 172 in any suitable manner not shown. The webs 173 of the pads at their opposite upper ends are bolted as at 174 to plates 175. These plates 175 lie on opposite sides of the webs 173 and embrace the same. The outer ends of the plates 175 are spaced apart to receive therebetween the end of a reciprocating bar 176. The bar 176 near its end has a notch or slot 178 cut into it from the top edge and in this notch is snugly disposed a cross block 179 the reduced rounded ends 180 of which are received in suitable bores in the ends of the plates 175. Thus the blocks 179 are connected to the plates 175 and through them to the webs 173 and can move up and down slightly with respect to the reciprocating bar elements 176. Threaded stems 181 are received in threaded bores in the ends of the bars 176 and extend upwardly above the tops of the bars 176 and at their tops are provided with hand knobs 182. A ring plate 183 is disposed around the stem 181 and rests upon the top edges of the plates 175. Between the knob 182 and the ring plate 183 is disposed a compression spring 184. By adjusting the stem 181 in its threaded bore the pressure on the spring 184 may be varied to vary the pressure on the plates 175 and through them on the webs so that the pressure on the pads on the surface of the cylinder D may be changed at will.

With particular reference to Figs. 25 and 26 it will be seen that the reciprocating bar elements 176 are slidably disposed in suitable ball races 185 which generally indicated by the numeral 185 which are disposed in housings 186 bolted at 187 to the frame members 90 of the cylinder D. At the left of these figures is shown the main gear 53 rotatable with the cylinder D and this meshes with a gear 188 mounted on a shaft 189 in the housing 186 and has a bevel gear 190 thereon meshing with another bevel gear 191 on a shaft 192 supported in the housing 186 having at its upper end a disk 193 on which a pin 194 is eccentrically mounted. This pin is connected to a link 195 which in turn is connected to another pin 196 on the end of a crank arm 197 fastened to the upper end of a shaft 198 supported in the housing 186. As shown in Fig. 25, this shaft 198 has thereon a gear 199 which on opposite sides meshes with racks 200 respectively disposed on the adjacent faces or wall of the pair of reciprocating bars 176 at this side of the buffer mechanism. Thus it is seen that the arrangement permits the buffer pads to be operated in pairs with the pads of each pair reciprocating in opposite directions. The pressure on the pads may be easily and quickly varied at will to make the buffing action as light or as heavy as desired.

16

Means for independently moving the powder cylinder

Referring now particularly to Figs. 32, 33, 34, and 35, it will be observed that there is provided a mechanism whereby the powder cylinder D may be quickly and easily disconnected from regular drive mechanism so that it may be inched along and independently moved for various reasons.

Supported across between the frame members 90 of the cylinder D is a rotatable shaft 201 which at its ends extends beyond the frame members 90 as shown. On one end the shaft has a pinion 202 meshing with the gear 53 on the cylinder D previously mentioned, and on the other end is a hand wheel or operating element 203. Between the hand wheel 203 and the frame 90 of the cylinder, there is fixed on the shaft 201 a collar 204 having peripheral grooves 205 and 206 therein and spaced apart. Pivoted to the frame 90 is a latch lever 207 having an arcuate edge 208 adapted to lie in one or the other of said grooves to latch the shaft 201 in one axial position or the other. In this manner the shaft is latched to hold it in position with the gear or pinion 202 in or out of mesh with the main gear 53 on the cylinder D. By turning the hand wheel 203 the cylinder D can thereby be inched around to any desired position by small degrees.

The cylinder D is provided with two spaced teeth 208 on its outer face near its periphery as shown in Figs. 7, 34 and 35 and the main purpose of the device just described is to move these teeth to a position where they will be aligned with mechanism in the chain delivery mechanism now to be described.

Figs. 34 and 35 show details of a mechanism which is not shown in detail in Fig. 7 to avoid complication of the showing. It involves the shaft 51 adjacent the cylinder D and at the forward end of the chain delivery mechanism C (Fig. 1). This shaft is supported in bearing blocks 209 and 210 having lugs 211 and 212 on their under faces. Links 213 and 214 are pivotally connected to these lugs. Disposed below the shaft 51 is a rock shaft 215 mounted on suitable supporting members 216 and 217. On the rock shaft 215 outside the supports 216 and 217 are collars 218 and 219 fixed thereon each having upstanding bifurcated lugs 220 and 221 pivotally connected to the lower ends respectively of the links 213 and 214. Connected to one end of the rock shaft 215 is a handle 222 which has a spring-pressed pin 223 near its upper end adapted to be swung with the handle to one of two positions at which are disposed apertured latch plates 224 and 225 to receive the pin 223 and latch the handle in one or the other of these two positions. When the handle 222 is in the vertical position the lugs and the connecting links are lined up in a vertical plane as shown in Fig. 34 and hold the shaft 51 at a definite level. When the handle is swung to the dotted position shown in Fig. 34, the lower lugs are swung to the right and thus swing the links away from the vertical thus pulling down on the bearing housings 209 and 210 and dropping the shaft 51 a determined amount.

Referring to Figs. 30 and 31 particularly, on the shaft 51 in a plane adjacent one side of the cylinder D is disposed a disk 226 with an integral hub 227 keyed to the shaft 51. This disk has upper and lower arcuate slots 228 and 229 therein in which ride the stems of headed bolts 230 and 231 respectively. The threaded ends of these bolts are supported in threaded engagement with 75 a vertically disposed plate 232 which is bored to

snugly surround the hub 227. At its top the plate 232 is provided with a single tooth 233. On opposite sides of the upper portion of the plate 232 are disposed adjustable set screws 234' and 235' mounted on blocks 236' and 237 on the disk 226. The screws are adjustable to bear against the sides of the plate 232 so as to adjust the position on the disk periphery of the tooth 233 for reasons which will be explained. When the tooth is thus adjusted then the bolts are tightened until another adjustment may be necessary.

By providing the mechanisms shown in these Figs. 30 to 35 inclusive it is possible to separate the powder cylinder from the drive of the press and then restore the separated units to their exact former relation quickly and easily.

Timing of gripper mechanisms

To precisely arrange the various elements so that their operative relations are timed for the purposes generally above set forth, we have, for instance, the adjustability of the forward end of the gripper cam bar 105 as shown in Fig. 36 wherein the main bar 105 is cut away to over-lap the similarly cut-away portion of the rear end of the forward portion of said bar. The two cutaway portions are nominated 105' and 105'' in Fig. 36. These overlapped portions are provided with suitable slots 106' and bolts 107' whereby the forward end of this cam bar may be exactly adjusted to dispose the levels thereon in the proper position with respect to rollers on the ends of the grippers shafts above referred to. Thus the levels of the end of the cam bar 105 may be accurately and precisely adjusted in determining the timing action of the gripper elements affected by said cam bar.

Timing adjustment of shaft 51 and gear 52

In order to properly adjust the grippers on the chain delivery carried by sprockets 68 shown in Fig. 7, so as to alter the relation between the sprockets and the drive sprocket 50, the construction shown in Figs. 37 and 38 is provided. In this drawing, on the shaft 51 there is keyed a hub 250, integrally provided with a bearing surface or cylinder 251 on which the gear 52 is rotatably disposed. This hub 250 is also provided with an integral disk 252 to which a series of bolts 253 are fixed and these bolts extend through arcuate slots 254 in the drive sprocket 50. It can be thus seen that without disturbing the position of the drive sprocket, the disk 252 may be adjusted with respect thereto and this will cause the precise adjustment of the shaft 51 and the gripper elements disposed thereon.

With the grippers thus aligned, it may be necessary to adjust the gear 52 so that when the toggle mechanism is restored to normal the gear 52 will properly mesh with the gear 53 on the cylinder D. If they do not properly mesh the gear 52 may be adjusted by means of the construction shown in Figs. 37 and 38. The face of the gear 52 adjacent the disk 252 is provided with a series of bolts 254 fixed thereto and projecting through arcuate slots 255 in the disk. At opposite points on its face the gear is also provided with studs 256 fastened by bolts 257 to the gear and projecting through openings 258 in the disk 252. The ends of these studs projecting through to the face of the disk 252 are provided with set screws 259 which are adapted to be positioned with respect to fixed blocks 260 on the face of the disk adjacent the ends of said studs. In this manner, with the bolts 254 loosened, the set screws 259

may be adjusted to precisely position the gear 52 with respect to the hub 250 and thereby in exact mesh with the gear 53 on the powder cylinder D.

Means for adjusting gripper fingers 95

Each set of fingers 95 on the several wells 91 of the cylinder D may be separately and independently adjusted by the means shown in Fig. 17 and these include the block 101 which is associated with both the rollers 93 and 94 to permit these rollers to be adjusted to precisely control the time of their operation by their respective cam bars. A further adjustment of the fingers 95 themselves is permitted by means of the fact that the gripper shaft 92 is keyed to block 92' and this block is related to the supporting bracket 95' and can be precisely adjusted with respect thereto by means of set screws 93' disposed on each side of the shaft 92 so as to tilt the block 92' and thereby angularly relate the fingers to the other cooperating associated elements. The anvil blocks 97 may also be adjusted by setting the screws 98 and 99 for the proper and desired timed functioning of these and related parts.

Excess color wiping mechanism

Referring now to Figs. 1 and 29, it is to be observed that a means is provided for wiping the surface of the cylinder D after the gap closers are opened so that the color which may have been deposited along the edge of the closer on the sheet may be easily and gently removed. Briefly and essentially it comprises a drum or cylinder 234 operated by an independent constant speed motor (not shown). Attached to this drum are three or more strips 235 of soft plush, each strip as long as the cylinder D and of any suitable width. The strips are moved in a direction opposite to that of the cylinder D. These strips give the surface of the cylinder D a soft wiping action so as not to disturb the freshly printed image on the sheet.

Disposed above the cylinder 234 and contacted by the wiper strips 235 is a suction tube 237' connected to any suitable source of suction (not shown) whereby as the strips brush against it the suction removes any color thereon deposited. Also disposed adjacent the surface of the cylinder D below and beyond the cylinder 234 is another suction head or device 238 and the front end of this head is provided with a flat extension plate 236 which extends forwardly closely adjacent the surface of the cylinder D. This extension is disposed to lie in the path of the strips 235 so that these strips may slap against it and any color left on the strips is knocked off and can be sucked into the head 238 which is connected to any suitable source of suction (not shown). The purpose of this extension 236 is to prevent the strips 235 from slapping against the freshly printed and dusted sheets. The extension takes this blow and the strips smoothly slide over the sheet between the extension thus providing a soft wiping and cleaning action.

Removal of color from back of sheets

In order to remove excess color from the backs of the sheets there is provided a suction box 239 (Fig. 1) connected by pipe 240 to any suitable source of suction (not shown). The top of this box is open and on it are supported a plurality of sheet-supporting rollers 241 across which the backs of the sheets pass and on which it is supported as the chain delivery mechanism E passes the sheets from the cylinder D to the pile-up delivery device F. As the sheet passes

across the rollers 241 it tends to partially close the top of the box and thus makes the suction more effective to hold the sheets firmly against the rollers to enable them to effectively remove the color on the back of the sheet. Any color thus removed is then sucked off to a suitable collecting point. The rollers 241 are preferably plush-covered and driven by means (not shown) to move their peripheries in a direction opposite to the motion of the sheets.

Final wiping of the cylinder surface

Referring to Fig. 1, there will be seen at the lowest point on the cylinder D a wiper brush 242 on a shaft 243 and this brush shaft is driven by a belt 244 from the shaft of a small motor 245. At this point, the gap closers on a cylinder D are open and disposed within the well 31. This permits the surface of the cylinder adjacent the edge of the well to be given a final cleaning action before a new sheet is gripped so that no powder or color will be formed at this point on the back of the newly introduced sheet.

Summary of general operation

The sheets are fed from the pile A of sheets automatically in a well known manner and through the rotary offset press B which may be of any suitable type but can be a press such as the Harris press adapted to print the design on the sheet in varnish instead of in colored ink. This press is provided with the usual chain delivery mechanism involving a series of spaced separate gripper fingers as above described. These gripper devices pass around an arcuate line closely adjacent the surface of the powder cylinder which line at a particular point is tangent to the cylinder surface. At this tangential point cams related to the chain delivery mechanism open the grippers to release the sheet. The sheets are gripped as they pass from the press impression rollers by any suitable well known mechanism (not shown).

The powder cylinder is provided with a series of gripper wells or cavities in which are disposed gripper and gap closer shafts. On the gripper shaft are a series of spaced gripper fingers operated to be opened and closed in timed manner by cams on the frame of the cylinder D. These cams are so situated that the gripper fingers on the cylinder are open when they get to the tangential point above mentioned, and are instantly closed thereat to grip the sheet and at the same approximate instant the grippers on the chain delivery mechanism, which have gripped the sheet up this point, are released to transfer the sheet without control of the sheet being relinquished for an instant. Reference to Figs. 13 and 14 show the relation of the grippers at this crucial instant. Fig. 13 views the mechanism in the direction of the lower arrow shown in Fig. 14, and shows how the grippers on the two mechanisms are spaced apart and separate so that they can grip and release the sheet to transfer the sheet without losing control of it. In order to accomplish this instantaneous transfer the improved machine thus provides a series of individual grippers on the powder cylinder so spaced that they come in a line between the grippers on the chain delivery mechanism. This makes it possible to take hold of the sheet with the cylinder grippers before the grippers on the chain delivery mechanism have let go of it.

Having effected thus the transfer of the sheet it becomes necessary to close the gap of the grip-

per well on the cylinder D so that the dry color in the fountains do not fall into the well. This is achieved by the gap closer which normally lies within the well but at the proper instant is swung around to close the gap and operated by separate mechanism including a cam on the cylinder frame.

When the gap closers are closed the sheet grippers on the cylinder must be somewhat below the surface of the cylinder so that the gap closer may lie smooth and flush with the cylinder surface. This result is achieved as above set forth in detail, by having the grippers on the cylinder mounted on spring supported anvils which tend to move the fingers out slightly beyond the surface of the cylinder when opened but which anvils are forced back by the fingers in their closing or gripping movement.

With the sheet thus transferred and gripped by the fingers on the cylinder and with the gap of the well closed tight the cylinder moves around past the fountains of which there are two with buffer pad mechanisms between the fountains and with several buffer pad mechanisms disposed beyond the last fountain so as to give the sheet a thorough buffing to incorporate the color into the varnish design and to loosen the color on the sheet outside the design.

By providing a powder cylinder at least four times the diameter of the printing cylinder, it is possible to have two fountains, a plurality of buffer mechanisms and four gripper wells on the cylinder, while at the same time, the fountains and buffers occupy substantially only the first quadrant of the cylinder surface from the right side of the horizontal line through its axis up to the vertical line drawn through the same axis. The color tends to fall back away from the pads. The last pads have little color to handle and act mainly as fine distributing pads. The springs on the pads may be adjusted to produce the desired light or heavy action. This therefore, keeps the powder on the cylinder from being carried too definitely beyond the top of the cylinder with consequent embarrassing results. By the time the sheets get to the top of the cylinder there is substantially no loose powder thereon and what little there is, is removed effectively by the several devices herein set forth for that purpose.

By thus providing a large cylinder capable of supporting several sheets at a time, the cylinder can be rotated at a reasonable angular speed but with a peripheral speed sufficient to receive sheets from the press at a rate of about four to five thousand sheets an hour which is far above the capacity of the flat bed presses previously used. This operation at much higher speed is also effected with complete control of the sheet at all times and with the avoidance of any pile-ups usually heretofore frequently encountered.

Another advantage of the large cylinder is that the sheet may be effectively powdered and dusted and yet the rear end of the sheet thus treated has passed the last treatment zone before its front edge, under gripper control, is at the point where the grippers on the cylinder are timed to open and pass the sheet to the pile-up mechanism E in the manner herein set forth. This physical fact thus permits the sheet to be free of any drag on it due to treatment apparatus at the instant it is transferred and therefore the liability of any missing or pile-up is eliminated.

In view of the construction and operation above set forth, it is obvious to one skilled in the art that the timing of the various elements is a

matter of careful adjustment of these elements which cooperate in combination to produce the results set forth. For instance, by throwing the toggle mechanism shown in Fig. 35 to disconnect the gears 52 and 53, the press and its chain delivery unit C may be operated to set the gripper bars shown in Fig. 3 at such an angle that they lie at the approximate point of tangency with the surface of the powder cylinder D. The cylinder D is then inched along by means of the mechanism shown in Fig. 32 until a well with its gripper shaft 92 (Fig. 15) is disposed also at this point of tangency as indicated in Fig. 14 and also Fig. 13. With the elements at this position, it is apparent that the grippers on the chain delivery unit C can be precisely adjusted by means of the adjustable cam 76 in Fig. 9 and the relation of the chain delivery can be adjusted by adjusting its supporting shaft 51 with respect to the drive sprocket 50 by the means shown in Figs. 37 and 38.

At the same time the grippers in the thus presented well can be precisely timed by adjusting the front end of the cam bar 105 as shown in Fig. 36 and by adjusting the blocks 101 and 92' shown in Fig. 17. The adjustment of grippers on the cylinder in subsequent wells may be also adjusted with respect to their operation by the means shown in Fig. 17. The timing of the well grippers with respect to the release of the sheet to the delivery mechanism E may be precisely timed by the adjustment of the roller 94 at the other end of the shaft 92 by means of their blocks 101 associated with these rollers and with respect to the cam 114 shown in Fig. 21.

With the parts thus adjusted and timed precisely the toggle mechanism is restored and the gears 52 and 53 brought into mesh. If because of the adjustments thus effected the gear is not in line to mesh exactly with the gear 53 then the means shown in Fig. 38 may be adjusted to effect their exact meshing.

The parts having thus been adjusted and the powder cylinder physically again related to the press the mechanism shown in Figs. 30 and 31 may be adjusted to aline the tooth 233 with the female element 208 on the adjacent face of the powder cylinder D (Fig. 7) so that when the cylinder D and the press are connected for operation these two elements will be alined. This engagement of the tooth 233 with the female elements 208 is merely to provide a means to permit the cylinder D and the transfer shaft 51 to be easily and precisely alined after having once been set as above mentioned in the event that it may become necessary at any time to throw the toggle mechanism down to separate them for the purpose of inching the cylinder D around for cleaning or other purposes. The parts having once been set and the grippers and related elements precisely timed as above mentioned it is thereafter necessary merely to aline the teeth 233 and 208 to be sure that the chain delivery shaft 51 and the cylinder D are in the right angularly alined position.

Thus it will be seen that the machine as to its separate units and taken as a whole presents a combination of units efficiently operable at high speed to print sheets, powder and/or dust them, and pass them to a pile-up device with complete elimination of pile-ups or stoppages of the machine due to lack of control of the sheets at any instant of time in their passage through the device. The sheets are thus efficiently powdered or floured and dusted with substantially no loss

of the powder, which, as to the color pigments, is very expensive, and may then be passed to another machine having an automatic feeder to be further treated in any other manner if desired. 5 Each unit operates with the others to achieve the desired end result and the various operations are precisely timed and regulated to eliminate interruptions and to afford a substantially automatic procedure from start to finish. 10 It is clear that the powdering cylinder may be used with the chain delivery mechanisms on either side and without the press to pass sheets already printed therethrough merely for the purpose of flouting or dusting them if that may be thought desirable. It is also possible to lift the pads and color fountains on the cylinder D by any suitable means (not shown) so that the press and the cylinder D may be used merely to print sheets in an ordinary manner and pass them to a pile-up device so that the device will act as an ordinary printing unit but with the complete control and regulated passage of the sheets. Therefore, without taking down the machine it can be used for other purposes with a minimum of time and expense. 15 While the invention has been described in detail and with respect to the preferred form shown in the drawings, it is not to be limited to such details and forms since many changes and modifications may be made in the invention without departing from the spirit and scope of the invention in its broadest aspects. Hence, it is intended to cover any and all forms and modifications of the invention which may come within the 20 language and/or scope of any one or more of the appended claims.

What I claim as my invention, is:

1. In a machine of the class described, the combination of a rotary printing press, a rotary powder cylinder disposed adjacent the press and having at least one powder fountain, the surface of the cylinder forming one wall of the fountain, a pile-up device on the other side of the cylinder, sheet delivery means disposed between the press and the cylinder and between the cylinder and the pile-up device adapted to transfer sheets to and from the cylinder, grippers on the delivery means and the cylinder to grip and move the sheets, and synchronizing means coupled with said sheet delivery means and with said cylinder so that each sheet is always under constant control of one of the several sets of grippers.
2. In a machine of the class described, the combination of a rotary printing press, a rotary powder cylinder disposed adjacent the press and having at least one powder fountain, the surface of the cylinder forming one wall of the fountain, a pile-up device on the other side of the cylinder, sheet delivery means disposed between the press and the cylinder and between the cylinder and the pile-up device adapted to transfer sheets to and from the cylinder, grippers on the delivery means and the cylinder to grip and move the sheets, and means for operating the grippers to transfer the sheets under continuous positive gripper control so that a subsequent set of grippers grips the sheet before the prior set has released it.
3. In a machine of the class described, a rotary powder cylinder, a plurality of color fountains disposed at vertically spaced levels across the face of said cylinder and up along the face of the cylinder substantially from a horizontal plane to a vertical plane through the axis thereof, the face of said cylinder forming a wall of each foun-

tain, a series of buffer elements between the fountains, and a series of buffer elements disposed above the upper fountain and horizontal plane through the axis of the cylinder, said buffer elements disposed across the face of said cylinder and constantly bearing upon said cylinder, and means for rotating said cylinder in a direction whereby each point on its face first passes the lowermost fountain.

4. In a machine of the class described, a rotary powder cylinder, a series of sheet treating devices disposed at vertical levels up along the surface of the cylinder, said sheet treating devices constantly bearing upon said cylinder in smooth fashion, means for rotating said cylinder in a direction whereby each point on its surface first passes the lowermost device, a series of grippers on said cylinder to pass a sheet around with the same to be treated, means to open the grippers, said sheet being treated in one revolution of the cylinder, a pile-up device beyond the cylinder, delivery means between the cylinder and the pile-up device to pass a sheet to the pile-up device, and means for applying suction to the back of the sheet only as it passes through the delivery means, said sheet treating devices being disposed up along the surface of the cylinder substantially from a horizontal plane to a vertical plane through the axis thereof and further being disposed substantially on the side of the cylinder opposite the pile-up device.

5. In a machine of the class described, a rotary powder cylinder, a series of sheet treating devices disposed at vertical levels up along the surface of the cylinder, means for rotating said cylinder in a direction whereby each point on its surface first passes the lowermost device, said sheet treating devices constantly bearing upon said cylinder in smooth fashion, a series of grippers on said cylinder to pass a sheet around with the same to be treated, and means to open the grippers when the sheet has been treated, said sheet being treated in one revolution of the cylinder, means cooperating with the cylinder to wipe the printed surface of the sheet after it has been treated, a pile-up device beyond the cylinder, delivery means between the cylinder and the pile-up device to pass a sheet to the pile-up device, and means for applying suction to the back of the sheet only as it passes through the delivery means, said sheet treating devices being disposed up along the surface of the cylinder substantially from a horizontal plane to a vertical plane through the axis thereof and further being disposed substantially on the side of the cylinder opposite the pile-up device.

6. In a machine of the class described, a rotary powder cylinder, a series of sheet treating devices disposed up along the surface of the cylinder from a horizontal plane to a vertical plane through its axis, said sheet treating devices constantly bearing upon said cylinder in smooth fashion, a series of grippers on said cylinder to pass a sheet around with the same to be treated, and means to open the grippers when the sheet has been treated, the size of the cylinder being such that the rear edge of any sheet has passed the treatment area before the front edge is released by the grippers, means cooperating with the cylinder to wipe the printed surface of the sheet after it has been treated, said wiping means comprising a plurality of whirling cloths and a cloth deflecting means, a pile-up device beyond the cylinder, delivery means between the cylinder and the pile-up device to pass a sheet to

the device, and means employing suction for wiping the back of the sheet as it passes through the delivery means.

7. In a device of the class described, a rotary printing press, a rotary powdering cylinder disposed adjacent the press and having at least one powder fountain, the surface of the cylinder forming one wall of the fountain, a pile-up delivery mechanism disposed on the opposite side of the cylinder, chain delivery means for feeding sheets from the press to the cylinder and from the cylinders to the pile-up mechanism, and grippers on both feeding means and on the cylinder to maintain the fed sheets under constant positive gripping control from the time they are printed until they are delivered to the pile-up mechanism.

8. In a device of the class described, a rotary printing press, a rotary powdering cylinder disposed adjacent the press and having at least one powder fountain, the surface of the cylinder forming one wall of the fountain, a chain delivery mechanism including grippers for gripping a sheet as it is printed and passing it to the cylinder, grippers on the cylinder, and means cooperating with the grippers on the cylinder to cause them to grip the sheet before the other grippers release the sheet so that the sheet is under continuous positive gripper control.

9. In a device of the class described, a rotary powdering cylinder, sheet gripping elements thereon, a plurality of powder fountains disposed at vertical levels along the surface of the cylinder, the surface of the cylinder forming a wall of each fountain, a pile-up mechanism adjacent the cylinder adapted to receive powdered sheets therefrom, a chain delivery mechanism between the cylinder and the pile-up mechanism, sheet gripping elements on said chain delivery mechanism, and means cooperating with the cylinder gripping elements and the gripping elements on the chain delivery mechanism to cause the gripping elements on the chain delivery mechanism to grip the sheets before the gripping elements on the cylinder are released therefrom, the sheet gripping elements on the cylinder adapted to hold the sheets until all treatment of the sheets on the cylinder is finished, the powder fountains being disposed along the surface of the cylinder substantially from a horizontal plane to a vertical plane through the axis thereof and further being disposed on the side of the cylinder opposite the pile-up mechanism.

10. In a device of the class described, a rotary printing press cylinder, a rotary powdering cylinder disposed adjacent the press cylinder and having at least one powder fountain, the surface of the powdering cylinder forming a wall of the fountain, said powdering cylinder adapted to receive a sheet from said press cylinder by means of a chain delivery mechanism and to carry said sheet around for treatment, said chain delivery mechanism including grippers for gripping the sheet as it is printed and passing it to the powdering cylinder, grippers on the powdering cylinder, a pile-up mechanism on the side of the powdering cylinder opposite from the printing press cylinder to receive the powdered sheets therefrom, a chain delivery mechanism between the powdering cylinder and the pile-up mechanism, grippers on said last mentioned chain delivery mechanism, and means cooperating with the grippers on the powdering cylinder and the other grippers mentioned to cause the sheet to be under constant gripping control until it is

delivered to the pile-up mechanism, the diameter of the powdering cylinder being at least four times greater than the diameter of the press cylinder so that the tail end of the sheet being treated on said powdering cylinder is treated prior to release of the front end thereof regardless of the sheet size.

11. In a device of the class described, a rotary printing press cylinder, a rotary powdering cylinder disposed adjacent the press cylinder and having at least one powder fountain, the surface of the powdering cylinder forming a wall of the fountain, said powdering cylinder adapted to receive a sheet from said press cylinder by means of a chain delivery mechanism and to carry said sheet around for treatment, said chain delivery mechanism including grippers for gripping the sheet as it is printed and passing it to the powdering cylinder, grippers on the powdering cylinder, a pile-up mechanism on the side of the powdering cylinder opposite from the printing press cylinder to receive the powdered sheets therefrom, a chain delivery mechanism between the powdering cylinder and the pile-up mechanism, grippers on said last mentioned chain delivery mechanism, and means cooperating with the chain delivery mechanism and the powdering cylinder whereby as the sheet is passed from the press cylinder through to the pile-up device the grippers engaging the sheet at any instant do not release it until the next set of grippers have engaged it, the diameter of the powdering cylinder being at least four times greater than the diameter of the press cylinder so that the tail end of the sheet being treated on said powdering cylinder is treated prior to release of the front end thereof regardless of the sheet size.

12. In a machine of the class described a rotary powder cylinder having a gripper well disposed across and opening into its periphery, a gripper shaft within the well and extending at its ends beyond the sides of the cylinder, a gripper finger on and operated by said shaft, a spring-supported anvil engaged by said finger, cam means operatively connected with the shaft to move the finger against the anvil, the anvil and finger when thus engaged being pressed back against the action of the spring to lie within the area of the well when the finger is moved against the anvil, the spring means when the finger is opened moving the anvil to a position where the anvil lies outside the periphery of the cylinder.

13. In a machine of the class described, a rotary powder cylinder having a gripper well disposed across and opening into its periphery, a gripper shaft within the well and extending at its ends beyond the sides of the cylinder, a series of gripper elements spaced apart along said shaft, and a plurality of cam means operatively connected with the cylinder to cooperate with said shaft to open and close said grippers at predetermined points in the rotation of said cylinder, a gap closer plate within the well, a shaft for said closer having one end extending beyond the side of the cylinder, and cam means operatively connected with the cylinder and cooperating with the closer shaft to operate the closer plate in timed sequence to open and close said closer plate to close the opening of the well when the grippers are in closed position.

14. In a machine of the class described, a rotary powder cylinder having a gripper well disposed across an opening into its periphery, a gripper shaft within the well and extending at its ends beyond the sides of the cylinder, a series

of gripper elements spaced apart along said shaft, rollers on the ends of said shaft, and cam elements operatively connected with opposite sides of said cylinder to cooperate with said rollers to open and close said grippers at predetermined points in the rotation of said cylinder, a gap closer plate within the well, a shaft for said closer plate having one end extending beyond the side of the cylinder, and cam means operatively connected with the cylinder and cooperating with the closer shaft to operate the closer plate in timed sequence to open and close the closer plate to close the opening of the well when the grippers are in closed position.

15. In a machine of the class described a rotary powder cylinder having a gripper well disposed across and opening into its periphery, a gripper shaft within the well and extending at its ends beyond the sides of the cylinder, a gripper finger on and operated by said shaft, a spring-supported anvil engaged by said finger, cam means operatively connected with the shaft to move the finger against the anvil, the anvil and finger when thus engaged being pressed back against the action of the spring to lie within the area of the well when the finger is moved against the anvil, the spring means when the finger is opened moving the anvil to a position where the anvil lies outside the periphery of the cylinder, a gap closer plate within the well, a shaft for said closer plate having one end extending beyond the side of the cylinder, and cam means operatively connected with the cylinder and cooperating with the closer shaft to operate the closer plate in timed sequence to open and close the closer plate to close the opening of the well when the finger is in closed position.

16. In a machine of the class described, a rotary powder cylinder having a gripper well disposed across and opening into its periphery, sheet grippers in said well, a gap closer plate pivotally disposed within said well, a shaft on which said closer plate is mounted, said shaft extending beyond the side of the cylinder, a cam roller on the end of the shaft, and a cam bar operatively connected with the cylinder and engaging said roller to pivot said shaft to move said closer plate to open and close the opening of the well at predetermined points in the rotation of the cylinder.

17. In a machine of the class described, a rotary powder cylinder having a gripper well disposed across and opening into its periphery, sheet grippers in said well, a gap closer plate pivotally disposed within said well, a shaft on which said closer plate is mounted, said shaft extending beyond the side of the cylinder, a cam roller on the end of the shaft, and a cam bar operatively connected with the cylinder and engaging said roller to pivot said shaft to move said closer plate to open and close the opening of the well at predetermined points in the rotation of the cylinder, the width of the closer plate being less than the width of the opening of the well, and a spring plate extending over the edge of the well to resiliently engage the rear edge of the closer plate to form a tight joint therewith.

18. In a machine of the class described, a rotary powder cylinder having a gripper well disposed across and opening into its periphery, a gap closer plate pivotally disposed within said well, a shaft on which said closer plate is mounted, said shaft extending beyond the side

of the cylinder, a cam roller on the end of the shaft, and a cam bar operatively connected with the cylinder and engaging said roller to pivot said shaft to move said closer plate to open and close the opening of the well at predetermined points in the rotation of the cylinder, the width of the closer plate being less than the width of the opening of the well, and a spring plate extending over the edge of the well to resiliently engage the rear edge of the closer plate to form a tight joint therewith, the forward portion of the closer plate being tapered to a thin edge to lie flush with the surface of the cylinder when the closer plate is closed.

19. In a machine of the class described, a rotary powder cylinder having a gripper well disposed across and opening into its periphery, a gripper shaft within the well and extending at its ends beyond the sides of the cylinder, a series of gripper elements spaced apart along said shaft, and a plurality of cam means operatively connected with the cylinder to cooperate with said shaft to open and close said grippers at predetermined points in the rotation of said cylinder, a gap closer plate pivotally disposed within said well, a shaft on which said closer plate is mounted, said closer shaft extending beyond the side of the cylinder, a cam roller on the end of the closer shaft, and a cam bar operatively connected with the cylinder and engaging said roller to pivot said closer shaft to move said closer plate to open and close the opening of the well at predetermined points in the rotation of the cylinder.

20. In a machine of the class described, a rotary powder cylinder having a gripper well disposed across and opening into its periphery, a gripper shaft within the well and extending at its ends beyond the sides of the cylinder, a series of gripper elements spaced apart along said shaft, rollers on the ends of said shaft, and cam elements operatively connected with opposite sides of said cylinder to cooperate with said rollers to open and close said grippers at predetermined points in the rotation of said cylinder, a gap closer plate pivotally disposed within said well, a shaft on which said closer plate is mounted, said closer shaft extending beyond the side of the cylinder, a cam roller on the end of the closer shaft, and a cam bar operatively connected with the cylinder and engaging said roller to pivot said closer shaft to move the closer plate to open and close the opening of the well at predetermined points in the rotation of the cylinder.

21. In a machine of the class described a rotary powder cylinder having a gripper well disposed across and opening into its periphery, a gripper shaft within the well and extending at its ends beyond the sides of the cylinder, a gripper finger on and operated by said shaft, a spring-supported anvil engaged by said finger, cam means operatively connected with the shaft to move the finger against the anvil, the anvil and finger when thus engaged being pressed back against the action of the spring to lie within the area of the well when the finger is moved against the anvil, the spring means when the finger is opened moving the anvil to a position where the anvil lies outside the periphery of the cylinder, a gap closer plate pivotally disposed within said well, a shaft on which said closer plate is mounted, said closer shaft extending beyond the side of the cylinder, a cam roller on the end of the closer shaft, and a cam bar operatively con-

nected with the cylinder and engaging said roller to pivot said closer shaft to move the closer plate to open and close the opening of the well at predetermined points in the rotation of the cylinder.

22. In a machine of the class described, a rotary powder cylinder having a gripper well disposed across and opening into its periphery, a series of spaced sheet grippers housed in said well and disposed along a longitudinal line on the periphery of said cylinder, a gap closer plate pivotally disposed within said well, delivery means having a series of spaced grippers to engage the forward edge of a sheet, the delivery grippers moving in a line at one point tangent to the periphery of the cylinder, and means operatively connected with the two sets of grippers to cause one set to grip the forward edge of the sheet before the other set of grippers has released said edge, the sheet grippers on the cylinder adapted to hold the sheets until all sheet treatment on the cylinder is completed.

23. In a machine of the class described, a rotary powder cylinder having a gripper well disposed across and opening into its periphery, a series of spaced sheet grippers housed in said well and disposed along a longitudinal line on the periphery of said cylinder, a gap closer plate pivotally disposed within said well, means to actuate said gap closer plate, delivery means having a series of spaced grippers to engage the forward edge of a sheet, the delivery grippers moving in a line at one point tangent to the periphery of the cylinder, and cam means operatively connected with the delivery means and the cylinder and cooperating with the two sets of grippers to cause one set to grip the forward edge of the sheet before the other set of grippers has released said edge, the sheet grippers on the cylinder adapted to hold the sheets until all sheet treatment on the cylinder is completed.

24. In a machine of the class described, a rotary powder cylinder, means thereon to grip a sheet to be dusted, a plurality of powder fountains circumferentially spaced apart along the periphery of the cylinder parallel to the axis thereof, the lower fountain being approximately in a line just above a horizontal plane passing through the axis of the cylinder, means to rotate said cylinder so that each point on its surface first passes the lower fountain, and a plurality of alternately and laterally reciprocating buffer mechanisms disposed between said fountains to dust the powder on the surface of the sheet, said buffer mechanisms constantly bearing upon said cylinder in smooth fashion.

25. In a machine of the class described, a rotary powder cylinder, means thereon to grip a sheet to be dusted, a plurality of powder fountains circumferentially spaced apart along the periphery of the cylinder parallel to the axis thereof, the lower fountain being approximately in a line just above a horizontal plane passing through the axis of the cylinder, means to rotate said cylinder so that each point on its surface first passes the lower fountain, and a plurality of alternately and laterally reciprocating buffer mechanisms disposed between said fountains to dust the powder on the surface of the sheet, and a plurality of other similarly reciprocating buffer mechanisms disposed in similar lines in engagement with the surface of the cylinder above the upper fountain, all said buffer mechanisms constantly bearing upon said cylinder in smooth fashion.

26. In a machine of the class described, a rotary powder cylinder, means thereon to grip a sheet to be dusted, a plurality of powder fountains circumferentially spaced apart along the periphery of the cylinder parallel to the axis thereof, the lower fountain being approximately in a line just above a horizontal plane passing through the axis of the cylinder, means to rotate said cylinder so that each point on its surface first passes the lower fountain, and a plurality of alternately and laterally reciprocating buffer mechanisms disposed between said fountains to dust the powder on the surface of the sheet, and a plurality of other similarly reciprocating buffer mechanisms disposed in similar lines in engagement with the surface of the cylinder above the upper fountain, all said buffer mechanisms constantly bearing upon said cylinder in smooth fashion, the fountains and the buffer mechanisms spaced apart to occupy not more than substantially the surface of the cylinder from the horizontal plane through the axis to the vertical plane therethrough.

27. In a machine of the class described a rotary powder cylinder, a color fountain disposed adjacent the surface of the cylinder, the surface of the cylinder forming one wall of the fountain, an adjustable plate forming the bottom of the fountain, side walls on said bottom plate, and having curved slots therein on adjacent faces, and a curved plate forming the rear wall of the fountain and removably disposed in said slots.

28. In a machine of the class described a rotary powder cylinder, a color fountain disposed adjacent the surface of the cylinder, the surface of the cylinder forming one wall of the fountain, an adjustable plate forming the bottom of the

5
10
15
20

fountain, side walls on said bottom plate, and having curved slots therein on adjacent faces, and a curved plate forming the rear wall of the fountain and removably disposed in said slots, a stirrer shaft disposed within the fountain, stirrer fingers dependent from said shaft into the fountain, and means operatively connected with the shaft and actuated by the rotation of the cylinder to reciprocate the fingers to stir the color in the fountain.

29. In a machine of the class described, a rotary powdering cylinder, a chain delivery mechanism to receive sheets from said cylinder, a suction box having an open top and rollers disposed in said open top to brush the back of the sheets being passed along by said delivery mechanism, the suction applied to said box causing the sheets to press firmly against said rollers to make their brushing action more effective.
